UNITED STATES PATENT OFFICE.

GEORGE FREDERICK MANSBRIDGE, OF NEW BARNET, ENGLAND.

VARIABLE INDUCTANCE.

Application filed August 16, 1924, Serial No. 732,531, and in Great Britain August 27, 1923.

This invention relates to variable inductances similar to those shown and described in the specification of United States Letters Patent No. 893,340 of 1908 granted to me. 5 Variable inductances as heretofore proposed possess certain defects, chief among which are (a) their restricted range of variation, (b) their electrostatic capacity and (c) their bulkiness and inconvenient shape. Now, it 10 is the object of this invention to remove these defects and to obtain in a small and convenient form a variable inductance having a large range of variation and a small electrostatic capacity. 15 According to this invention the inductance elements are made of D-form, or substantially so, as explained in the aforesaid patent specification and wound so that their self capacity is minimized. This I do by winding in a single layer with space between each convolution and the next or by one of the well known anti-capacity methods e. g. that known as "basket" winding or I may 20 employ two-layer or multi-layer windings 25 wound in cellular, openwork, or other well known anti-capacity form. The inductance elements so prepared are mounted on discs in such manner that the mountings and their inductance elements can be rotated relatively 30 to one another in order to vary the inductance.

In order that this invention may be the more clearly understood and readily carried into effect, I will proceed to describe the 35 same with reference to the accompanying drawings, which illustrate by way of example, and not of limitation, the preferred embodiment of this invention, and wherein—

Figure 1 is a plan of the bottom disc 40 showing the inductance elements mounted therein, and

Figure 2 is an under plan of the top disc also showing the inductance elements mounted therein.

45 Figures 3 and 4 are under plan and plan respectively of the parts of the instrument as assembled.

Figure 5 is a section on line 5—5 of Figure 3.

50 Figure 6 is an elevation of the instrument. Referring to the drawings, the instrument comprises two discs *a* and *b*, preferably of ebonite or like insulating material. Mounted in the disc *a* are two kidney-shaped inductance elements *c* and *d* sunk slightly below the outer edge of the disc *a* and wound

so as to have a low self-capacity. These elements are wound in opposite directions and the outer end of element *c* is joined to the inner end of the element *d*. The inner end of the element *c* is connected to a terminal *c*¹ mounted on the underside of the disc *a*, and the outer end of element *d* is connected to a like terminal *d*¹. The disc *a* is provided with supporting legs *a*¹. 60

In the disc *b* are arranged two inductance elements *e* and *f* which are shaped, wound and arranged similarly to the inductance elements *c* and *d* which have their inner ends joined together. The outer ends of these 70 elements are joined at *e*¹ and *f*¹ to flexible leads *e*² and *f*² respectively. The leads pass through a metal plug *g* fixed to the disc *b* and the said plug is insulated from the inductance elements by an insulating sleeve *g*¹. 75 The lower portion of the plug is rotatably mounted in a bushing *a*² fixed in the disc *a*, and a nut *g*² is screwed on to the lower extremity of the plug to keep the discs together. 80

The free ends of the flexible leads *e*² and *f*² are attached to terminals *e*³ and *f*³ mounted on the underside of the disc *a*.

By sinking in the inductance elements, as above described, I obtain the optimum position of the best balance between maximum inductive effect and minimum capacity between the inductance elements on one disc and those on the other. 85

The upper edge of the disc *a* is provided 90 with an upstanding lip *a*³ adapted to take into a circumferential recess, *b*¹, formed in the lower edge of the disc *b*. The recess *b*¹ is of such length that, in conjunction with the lip *a*³, it limits the rotary movement of 95 one disc relatively to the other to 180°.

To the top of the disc *b* is vulcanized or otherwise secured a boss *b*² having a bevelled edge whereon is inscribed a scale of 180° which, in conjunction with a line marked 100 on a pointer *h*, secured to the disc *a*, indicates the angle through which the top disc has been rotated in order to vary the inductance. The rotation of the disc *b* is effected by means of a knob *b*³ which is fixed 105 on a rod *b*⁴, screwed into the plug *g*.

Strips of metal may be provided to form 110 connections between the terminals *c*¹, *d*¹, *e*³ and *f*³ so as to connect the inductance elements *c* and *d* and *e* and *f* either in series for high values or in parallel for low values.

It will be readily understood that by ro-

tating the top disc a smooth variation of the value of inductance between minimum and maximum will be obtained, since at one extreme position the superimposed inductance elements have an additive effect while at the other extreme position they have a subtractive effect.

The inductance elements are preferably "basket" wound or they may be wound by any other suitable known method designed to give low self-capacity.

According to a modification, the inductance elements are embedded in any suitable known substance having a low dielectric constant.

To increase the range of variation the inductance elements may be wound in two or more sections and means may be provided whereby one or more of the sections may conveniently be cut out of circuit.

In some cases the inductance elements may be of D-shape having the straight sides of each pair arranged contiguously, or they may be of circular or other than kidney shape.

Thus, by this invention the advantages of large range variability of inductance, con-

jointly with compactness of construction and low electrostatic capacity are obtained.

I claim:—

In a variable inductance, an upper disc having a partially circumferential groove, a lower disc having terminals on its underside and an upstanding stop, two substantially kidney-shaped inductance elements in each disc, a bushing in the lower disc, a metal plug carried by the upper disc and passing through the bushing in the lower disc, flexible connections from the inductance elements in the upper disc passing through the said plug to certain of the terminals on the underside of the lower disc, connections from the inductance elements in the lower disc to other of the said terminals, temporary switch members to bridge the said terminals so as to connect the said inductance elements either in series or in parallel at will, the arrangement being such that the said stop abuts against the end of the groove in the upper disc and limits the relative rotary movement of the two discs to 180°.

In testimony whereof I have signed my name to this specification.

GEORGE FREDERICK MANSBRIDGE.
